CLAIM

The ornamental design for a combination wireless charger and music lamp, as shown and described.

DESCRIPTION

FIG. 1 is a first perspective view of a combination wireless charger and music lamp showing my new design; FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a right side view of another state of the combination wireless charger and music lamp thereof; and,

FIG. 10 is an enlarged view of the selected portion 10 in FIG. 1.

The broken lines shown in the drawings depict portions of the combination wireless charger and music lamp that form no part of the claimed design.
